Application January 31, 1935, Serial No. 4,346
Renewed May 21, 1937

18 Claims. (Cl. 62—117)

This invention relates to refrigeration and more particularly to the conditioning of air for railway cars and the like.

It is an object of this invention to provide a way of driving a compressor on a railway car either from the axle of the car or from a motor and to provide an improved arrangement whereby the motor drives the compressor when the car runs below a predetermined speed or stands still and whereby the car axle drives the compressor when the car runs above a predetermined speed and also drives the generator to charge a battery when the car runs at sufficiently high speed.

Further objects and advantages of the present invention will be apparent from the following description, reference being had to the accompanying drawings, wherein a preferred form of the present invention is clearly shown.

In the drawings:

Fig. 1 is a diagrammatic representation of an embodiment of this invention;

Fig. 2 is a wiring diagram for the arrangement shown in Fig. 1;

Fig. 3 is a cross-sectional view of the driving pulley of the variable ratio drive; and

Fig. 4 is a cross-sectional view of the driven pulley of the variable ratio drive.

In the arrangement shown in Fig. 1, together with the wiring diagram shown in Fig. 2, the heat dissipator, including the compressor 10 is driven by a motor-generator 11 (acting as a motor) through a car speed zone, such as when the car stands or travels at a slow speed, such as below 15 M. P. H. The compressor is driven by a variable ratio drive from the axle of the car through another car speed zone, such as when the car travels at 15 M. P. H. or above. The arrangement is such that, as the speed of the car increases, say to approximately 15 M. P. H. the compressor is connected to the axle drive, but the generator is prevented from generating until the speed of the car reaches a third car speed zone including all speeds, say 25 M. P. H. and above. The purpose of such an arrangement is to prevent too large a transmission load on the variable ratio drive when the power transmission parts are not moving at high speeds.

In the arrangement shown, the axle 12 of the car is connected to the shaft 13, by means of a variable ratio drive. The shaft 14 is driven at a substantially constant speed when the car travels between certain speed limits, such as 15 to 90 M. P. H. The shaft 13 drives shaft 14 through beveled gears 15 and 16. The shaft 14 drives the

motor-generator shaft 17 through the medium of a clutch 18 and the necessary universal joint arrangement, one of the universal joints being shown at 19 and the other at 20. The motor-generator shaft 17 is drivingly connected to the compressor 10 through the medium of the multiple belt drive 21. A pneumatic clutch 22 is provided so that the motor-generator 11 can be disconnected from the compressor 10. This permits the motor-generator to be driven as a generator to charge the battery even when refrigeration is not required. The refrigerating system includes a heat dissipator which may take the form of compressor 10 connected to a condenser 23 and receiver 24 and a heat absorber which may take the form of an evaporator 25. A fan 27, driven by a motor 28, blows air over the evaporator 25 and into the compartment to be conditioned, the air coming from the outside through the conduit 29 provided with a filter 30 and/or from the inside of the car compartment through the conduit 31 under the control of dampers 32 and 33. The evaporator 25 may be of the type which is provided with a valve 34 having a thermostatic bulb 26 placed near the outlet of the evaporator and so arranged as automatically to maintain the cooling surfaces of the evaporator above 32° F. and to prevent frost-back between the evaporator and the compressor. This latter feature is accomplished by setting the automatic valve 34 to maintain a vapor pressure within the evaporator corresponding to a temperature above 32° F. but below the temperature to which the air is to be cooled.

Controls are provided for the clutches 18 and 22 and for the electrical circuit. A wiring arrangement for the controls is shown in Fig. 2. A battery 35a is provided with main leads 36 and 37. A generator 38, which may be comparatively small, if desired, is driven from the axle 12 and generates current in proportion to the speed of the car. This generator is connected to the solenoids 39, 40 and 41.

Referring now to Fig. 2, the manual switch 42 controls the flow of current to the motor fan 28 so that the fan 27 may be operated even when refrigeration is not required. The manual switch 43 controls the action of the refrigerating system. When switch 43 is closed, the refrigerating system is placed under the control of thermostat 44. When the temperature rises in the compartment of the car in which the thermostat 44 is placed, the contacts 45 are closed. This causes current to flow to the solenoid 46 which in turn controls the flow of air to the clutch 22 and causes the

clutch to close or come to the driving position, if the car is standing still or is running below 15 M. P. H. When the contacts 45 close, current also flows through line 47 and low voltage relay cutout 5 49 (coil 49a of which is placed across the battery 35a by lines 49b) to the starter coil 50 and from thence to the line 37. When the coil 50 is energized, the contacts 51 are closed. This causes the current from the battery to energize the motor. 10 This is accomplished because current flows from the line 36 through fuse 52, shunt plug 53, line 54, contacts 51, armature 55 of the motor-generator 11 to line 37. In addition current flows through the branch 56 and contacts 57, 58 15 through motor resistance 59 and motor shunt field 60 to the line 37.

At 15 M. P. H. the solenoid 39 opens the contacts 48 and moves the contact 57 to the contact 61. The opening of the contacts 48 cuts off the supply of current from the battery to the motor and thus permits the motor to stop. After a sufficient time delay to permit the motor to stop, and when the car reaches, say 18 M. P. H., the solenoid 40 closes the contacts 62. This energizes the solenoid 63 and causes air pressure to close clutch 18 through the medium of bellows 64. This causes the car axle 12 to drive the compressor 10; but the motor-generator does not at this time charge the battery. Thus the double load of the compressor and generator is not, at this time, placed on the relatively slow moving power transmission parts. While the car is traveling at 18 M. P. H. or above, the clutch 22 is still under the control of thermostat 44 and thus the compressor 10 is started and stopped in accordance with temperature conditions in the compartment of the car for which the air is being conditioned.

At 25 M. P. H. the motor-generator 11 is caused to charge the battery 35a. This is accomplished because, at 25 M. P. H., the solenoid 41 closes the contacts 65. This re-energizes the starter coil 50 which again closes the contacts 51. As the contact 57 is now in the dotted line position in contact with 61, current from the armature 55 flows through branch 56, contact 57, contact 61, variable resistance 62a, shunt field 60 to line 37 and back to the armature 55. The variable resistance 62a has its resistance increased as the voltage rises since the coil 63a is placed across the terminals of the armature 55. Coil 63a regulates the resistance of carbon pile 62a. Under these conditions the battery 35a is charged by the motor-generator since current can flow to the battery from the armature 55 through contacts 51, line 54, shunt plug 53, fuse 52 and line 36. If desired, an armature current limiting coil 65b may be placed across the terminals of the shunt plug 53 so that if the current becomes abnormally high while the generator is operating, the variable resistance 62a is increased, and thus the charging rate is decreased. Lights 64 may be placed across the battery 35a and may be controlled by switch 65.

65 The solenoids 39, 40 and 41 may be so arranged that when they have acted to close or open their respective contacts at a given train speed they maintain their respective contacts in the new position even if the train speed recrosses the 70 critical speed, until a sufficient change in speed has occurred to prevent chattering. Thus while solenoid 39 opens its contacts at 15 M. P. H. as the speed of the train increases, the contacts do not reclose until the train has slowed down to, say 13 M. P. H. or less. Likewise solenoid

40 may close its contacts as the train speed increases to 18 M. P. H. but will not open them again until the speed drops to say, 16 M. P. H. Solenoid 41 may close its contacts at 25 M. P. H. and open them at 22 M. P. H. It is to be understood that the speed limits given are by way of example, however, and that any other suitable speed limits may be chosen.

Any type of variable ratio drive may be placed between the car shaft 12 and the longitudinal shaft 14. However, we prefer to use the belt drive together with the variable diameter pulley arrangement shown more in detail in Figs. 3 and 4. Thus two driving pulley structures 80 and 80a are placed on shaft 12. These driving pulley structures may be substantially identical and are merely placed in diametric relationship with each other. These structures are connected by belts 81, 82, 81a and 82a with the driven pulley structures 83 and 83a respectively. The driven pulley structures 83 and 83a are fixed on the shaft 13 which carries the bevel gears 15 meshed with the beveled gear 16 and which drives the shaft 14 through the medium of the sliding keyway 14a and the universal joint 20. The shaft 14 is provided with another universal joint 19 which connects with the section 17 which may be carried by bearings on the main body of the car. The construction is such that the truck 70 may turn relatively to the main body and this change in position is compensated for by the sliding keyway 14a and the universal joints 19 and 20.

The variable ratio drives 15 and 16 may be identical, except that they are diametrically placed with respect to each other. The driving pulley structure 80 is shown more in detail in Fig. 3. It may include a pair of flanges 100, 101 which are fixed both rotationally and axially on the shaft 12. The flange 100 is fixed on the shaft 12 by the bolts 102 and by proper keys 40 between the cylinder 102a and the shaft 12. The flange 101 is fixed to the shaft 12 through the medium of rods 103 and 103a which in turn are secured to the flange 100. There are several rods 103 and 103a arranged about the shaft 12. 45 The rods 103a have sleeves 103b which lock the flange 101 axially. A pair of flanges 104 and 105 are so arranged that they move axially with respect to axle 12 and cause the belts 81 and 82 to move radially towards the shaft 12 as the speed of the axle 12 increases, and this movement is so calibrated that the shaft 13 is driven at a substantially constant speed while the car travels between certain speeds as will be hereinafter more fully described. Simultaneous 55 movement of the flanges 104 and 105 may be accomplished by providing a plurality of sleeves 106, which are fixed to the flanges 104 and 105, and which ride on the rods 103 through the bearings 107. The flanges 104 and 105 may thus 60 move axially with respect to the axle 12 by riding on the rods 103. A spring tension may be imposed on the flanges 104 and 105, and this may be accomplished by a plurality of springs 108 which bear against the flange 105 at one end 65 and against a flange 109 at the other end. The flange 109 may be placed in fixed relationship, both with respect to rotation and axial movement, on the shaft 12. This may be accomplished by mounting the flange 109 also on the rods 103 70 and 103a which in turn are fixed on the flange 100 which in turn is fixed on the shaft 12. The strength of the springs 108 is so chosen that the flanges 104 and 105 move axially the proper amount to maintain the shaft 13 substantially 75

at a constant speed, as hereinafter more fully described.

The driven pulley structure 83 is shown more in detail in Fig. 4. This structure may include a pair of flanges 110 and 111 which are fixed, both rotationally and axially, with relation to the shaft 13. This may be accomplished by fixedly keying the flange 110 on the shaft 13 at 112. The flange 111 is fixedly connected to the flange 110 through the medium of rods 113 and 114, there being several of the rods 113 and 114. The rods 113 are provided with sleeves 115 which, together with the washer 116, fixedly clamp the flange 111 with respect to the flange 110. A pair of relatively movable flanges 117 and 118 are provided. These flanges are keyed to each other by the sleeves 119 which ride on ball bearings 120 on the rods 114. The spacing between the flanges 117 and 118 is thus maintained constant; but the flanges 117 and 118 may move simultaneously axially with respect to the flanges 110 and 111.

The movement of the flanges 117 and 118 is governed by any suitable means which tends to maintain the shaft 13 at a substantially constant speed. Thus a plurality of centrifugal weights 120a may bear against the surfaces 121 and 122 and tend to spread them apart upon slight differential increase of speed. The spreading apart of these surfaces moves the flange 117 towards the flange 110 and the flange 118 towards the flange 111. Such a motion causes the belts 81 and 82 to move radially downward. Such belt motion is compensated for by a simultaneous movement of the belts radially inward on the driving pulley structure 80. Thus if the speed of the shaft 12 tends to increase, the belts 81 and 82 move downwardly on the driven pulley structure 83 and thus tend to increase the effective belt diameter on this structure. At the same time the belts move radially inward on the driving structure 80 and thus tend to decrease the "driving diameter" on this structure. The calibration of the centrifugal weights 80 and the strength of the springs 108 can be such that the speed of the shaft 13 can be maintained substantially constant within any desired constant speed limits, there being merely the slightest speed differential on the shaft 13, sufficient to permit the radial movement of the weights 120. Any suitable structure for the weights 120 may be used, but we prefer to use the weight structure disclosed in the copending application of Charles L. Paulus and Lester E. Perrine, Serial No. 742,490, filed September 1, 1934.

While the form of embodiment of the invention as herein disclosed, constitutes a preferred form, it is to be understood that other forms might be adopted, all coming within the scope of the claims which follow.

What is claimed is as follows:

1. In a vehicle; a live axle assembly; a compressor; a unitary motor-generator; a battery; torque transmitting means from said live axle assembly to said compressor and motor-generator; control means, automatically responsive to vehicle running conditions, to cause said motor-generator, to act as a motor energized from said battery, to drive said compressor independently of said live axle assembly when said vehicle is standing and, when said vehicle is in motion, to cause said live axle assembly to drive, through said torque transmitting means, said compressor and said motor-generator, said motor-generator arranged to act as a generator to charge said battery, and the generating field of said motor-generator being energized in a circuit in parallel with said battery.

2. In a vehicle; a live axle assembly; a compressor; a unitary motor-generator; a battery; torque transmitting means from said live axle assembly to said compressor and motor-generator and between said compressor and motor-generator; control means, automatically responsive to vehicle running conditions, to cause said motor-generator, to act as a motor energized from said battery, to drive said compressor independently of said live axle assembly when said vehicle is standing and, when said vehicle is in motion, to cause said live axle assembly to drive, through said torque transmitting means, said compressor and said motor-generator, said motor-generator arranged to act as a generator to charge said battery, and the generating field of said motor-generator being energized in a circuit in parallel with said battery.

3. In a vehicle; a live axle assembly; a compressor; a unitary motor-generator; a battery; torque transmitting means from said live axle assembly to said compressor and motor-generator and between said compressor and motor-generator; control means, automatically responsive to vehicle running conditions, to cause said motor-generator, to act as a motor energized from said battery, to drive said compressor independently of said live axle assembly when said vehicle is standing and, when said vehicle is in motion, to cause said live axle assembly to drive, through said torque transmitting means, said compressor and said motor-generator, said motor-generator arranged to act as a generator to charge said battery, and the generating field of said motor-generator being energized in a circuit in parallel with said battery, said control means including provisions to cause said compressor to perform a compressing action, while driven from said live axle assembly, at times when said motor-generator is not generating.

4. In a vehicle; a live axle assembly; a compressor; a unitary motor-generator; a battery; torque transmitting means from said live axle assembly to said compressor and motor-generator and between said compressor and motor-generator; control means, automatically responsive to vehicle running and refrigeration conditions, to cause said motor-generator, to act as a motor energized from said battery, to drive said compressor independently of said live axle assembly when said vehicle is standing and, when said vehicle is in motion, to cause said live axle assembly to drive, through said torque transmitting means, said compressor and said motor-generator, said motor-generator arranged to act as a generator to charge said battery and the generating field of said motor-generator being energized in a circuit in parallel with said battery, said control means including provisions to cause said motor-generator to perform a generating action while driven from said live axle assembly, at times when said compressor is not compressing.

5. In a vehicle; a live axle assembly; a compressor; a unitary motor-generator; a battery; torque transmitting means from said live axle assembly to said compressor and motor-generator and between said compressor and motor-generator; control means, automatically responsive to vehicle running conditions, to cause said motor-generator, to act as a motor energized from said battery, to drive said compressor independently of said live axle assembly when said vehicle is running below a certain speed limit and, when said vehicle is running above a certain speed limit, to cause said live axle assembly to drive, through said torque transmitting means, said compressor and said motor-generator, said motor-generator arranged to act as a generator to charge said battery, and the generating field of said motor-generator being energized in a circuit in parallel with said battery.

6. In a vehicle; a live axle assembly; a compressor; a unitary motor-generator; a battery; torque transmitting means from said live axle assembly to said compressor and motor-generator and between said compressor and motor-generator; control means, automatically responsive to vehicle running conditions, to cause said motor-

generator, to act as a motor energized from said battery, to drive said compressor independently of said live axle assembly when said vehicle is running below a certain speed limit and, when 5 said vehicle is running above a certain speed limit, to cause said live axle assembly to drive, through said torque transmitting means, said compressor and said motor-generator, said motor-generator arranged to act as a generator 10 to charge said battery and the generating field of said motor-generator being energized in a circuit in parallel with said battery, said control means including provisions for causing said compressor to perform a compressing action, while 15 driven from said live axle assembly, at times when said motor-generator is not generating.

6. In a vehicle; a live axle assembly; a compressor; a unitary motor-generator; a battery; torque transmitting means from said live axle 20 assembly to said compressor and motor-generator and between said compressor and motor-generator; control means, automatically responsive to vehicle running and refrigeration conditions, to cause said motor-generator, to act as a motor 25 energized from said battery, to drive said compressor independently of said live axle assembly when said vehicle is running below a certain speed limit and, when said vehicle is running above a certain speed limit, to cause said live 30 axle assembly to drive, through said torque transmitting means, said compressor and said motor-generator, said motor-generator arranged to act as a generator to charge said battery and the generating field of said motor-generator being 35 energized in a circuit in parallel with said battery, said control means including provisions to cause said motor-generator to perform a generating action while driven from said live axle assembly, at times when said compressor is not 40 compressing.

7. In a vehicle; a live axle structure; a battery; a refrigerating system on said vehicle including an evaporator, condenser and a unitary motor-generator; a compressor; torque transmitting 45 means from said live axle structure to said motor-generator and said compressor, and between said compressor and motor-generator; first clutch means between said live axle structure and said motor-generator and compressor; second clutch means between said motor-generator and compressor; speed responsive means to cause said first clutch means to disengage below a certain speed limit, refrigeration responsive means controlling the engagement of said second clutch 50 means, and provisions for automatically changing said motor-generator between motoring from said battery and charging said battery in response to running and refrigeration conditions, the generating field of said motor-generator being energized in a circuit in parallel with said battery. 55

8. In a vehicle; a live axle structure; a battery; a refrigerating system on said vehicle including an evaporator, condenser and a unitary motor-generator; a compressor; torque transmitting 60 means from said live axle structure to said motor-generator and said compressor, and between said compressor and motor-generator; first clutch means between said live axle structure and said motor-generator and compressor; second clutch means between said motor-generator and compressor; speed responsive means to cause said first clutch means to disengage below a certain speed limit, refrigeration responsive means controlling the engagement of said second 65 clutch means, and provisions for automatically 70

changing said motor-generator between motoring from said battery and charging said battery in response to running and refrigeration conditions, the generating field of said motor-generator being energized in a circuit in parallel 5 with said battery, the arrangement being such that said motor-generator can perform a generating action while driven from said live axle structure at times when said compressor is not compressing. 10

9. In a vehicle; a live axle structure; a battery; a refrigerating system on said vehicle including an evaporator, condenser and a unitary motor-generator; a compressor; torque transmitting means from said live axle structure to said 15 motor-generator and said compressor, and between said compressor and motor-generator; first clutch means between said live axle structure and said motor-generator and compressor; second clutch means between said motor-generator and compressor; speed responsive means to cause said first clutch means to disengage below a certain speed limit, refrigeration responsive means controlling the engagement of said second clutch means, and provisions for automatically changing 20 said motor-generator between motoring from said battery and charging said battery in response to running and refrigeration conditions, the generating field of said motor-generator being energized in a circuit in parallel with said 25 battery, the arrangement being such that said compressor can perform a compressing action while driven from said live axle structure at times when said motor-generator is not generating. 30

10. In a vehicle; a live axle structure; a battery; a refrigerating system on said vehicle including an evaporator, condenser and a unitary motor-generator; a compressor; torque transmitting means from said live axle structure to said 35 motor-generator and said compressor, and between said compressor and motor-generator; first clutch means between said live axle structure and said motor-generator and compressor; second clutch means between said motor-generator and compressor; speed responsive means to cause 40 said first clutch means to disengage below a certain speed limit, refrigeration responsive means controlling the engagement of said second clutch means, and provisions for automatically changing 45 said motor-generator between motoring from said battery and charging said battery in response to running and refrigeration conditions, the generating field of said motor-generator being energized in a circuit in parallel with said battery, the arrangement being such that said motor-generator can perform a generating action while driven from said live axle structure at times when said compressor is not compressing and that said 50 compressor can perform a compressing action while driven from said live axle structure at times when said motor-generator is not generating. 55

11. In a vehicle; a live axle structure; a battery; a refrigerating system on said vehicle including an evaporator, condenser and a unitary motor-generator; a compressor; torque transmitting means from said live axle structure to said 60 motor-generator and said compressor, and between said compressor and motor-generator; first clutch means between said live axle structure and said motor-generator and compressor; second clutch means between said motor-generator and compressor; speed responsive means to cause said first clutch means to disengage below a certain speed limit, refrigeration responsive means controlling the engagement of said 65

second clutch means, and provisions for automatically changing said motor-generator between motoring from said battery and charging said battery in response to running and refrigeration 5 conditions, the generating field of said motor-generator being energized in a circuit in parallel with said battery, said refrigeration responsive means controlling the operation of said compressor when driven by said motor-generator acting as a motor.

12. In a vehicle, a live axle assembly; a compressor; a unitary motor-generator; a battery; torque transmitting means from said live axle assembly to said compressor and motor-generator; 15 and between said compressor and motor-generator; control means, automatically responsive to vehicle running conditions, to cause said motor-generator to act as a motor energized from said battery, to drive said compressor independently of said live axle assembly when said vehicle is standing and, when said vehicle is in motion, to cause said live axle assembly to drive, through said torque transmitting means, said compressor and said motor-generator, said motor-generator arranged to act as a generator to charge said battery, said torque transmitting means including gearing belted to said live axle assembly, said gearing being connected to said motor-generator by a shaft longitudinal to the 20 car, and a clutch between said motor-generator and said live axle assembly.

13. In a vehicle, a live axle assembly; a compressor; a unitary motor-generator; a battery; torque transmitting means from said live axle assembly to said compressor and motor-generator; 25 and between said compressor and motor-generator; control means, automatically responsive to vehicle running conditions, to cause said motor-generator to act as a motor energized from said battery, to drive said compressor independently of said live axle assembly when said vehicle is standing and, when said vehicle is in motion, to cause said live axle assembly to drive, through said torque transmitting means, said compressor and said motor-generator, said motor-generator arranged to act as a generator to charge said battery, said torque transmitting means including gearing belted to said live axle assembly, said gearing being connected to said motor-generator by a shaft longitudinal to the 30 car, and a clutch between said motor-generator and said live axle assembly automatically responsive to vehicle running conditions.

14. In a vehicle, a live axle assembly; a compressor; a unitary motor-generator; a battery; torque transmitting means from said live axle assembly to said compressor and motor-generator; and between said compressor and motor-generator; control means, automatically responsive to vehicle running conditions, to cause said motor-generator to act as a motor energized from said battery, to drive said compressor independently of said live axle assembly when said vehicle is standing and, when said vehicle is in motion, to cause said live axle assembly to drive, through said torque transmitting means, said compressor and said motor-generator, said motor-generator arranged to act as a generator to charge said battery, said torque transmitting means including gearing belted to said live axle assembly, said gearing being connected to said motor-generator by a shaft longitudinal to the car, and said compressor being placed laterally of said motor-generator and belted to said motor-generator.

15. In a vehicle, a live axle assembly, a compressor; a unitary motor-generator; a battery; torque transmitting means from said live axle assembly to said compressor and motor-generator and between said compressor and motor-generator; control means, automatically responsive to vehicle running conditions, to cause said motor-generator to act as a motor energized from said battery, to drive said compressor independently of said live axle assembly when said vehicle is standing and, when said vehicle is in motion, to cause said live axle assembly to drive, through said torque transmitting means, said compressor and said motor-generator, said motor-generator arranged to act as a generator to charge said battery, said torque transmitting means including gearing belted to said live axle assembly, said gearing being connected to said motor-generator by a shaft longitudinal to the car, and a clutch between said motor-generator and said live axle assembly.

16. In a vehicle, a live axle assembly; a compressor; a unitary motor-generator; a battery; torque transmitting means from said live axle assembly to said compressor and motor-generator and between said compressor and motor-generator; control means, automatically responsive to vehicle running conditions, to cause said motor-generator to act as a motor energized from said battery, to drive said compressor independently of said live axle assembly when said vehicle is standing and, when said vehicle is in motion, to cause said live axle assembly to drive, through said torque transmitting means, said compressor and said motor-generator, said motor-generator arranged to act as a generator to charge said battery, said torque transmitting means including gearing belted to said live axle assembly, said gearing being connected to said motor-generator by a shaft longitudinal to the car, and means automatically responsive to refrigeration conditions modifying the operation of said compressor.

17. In a vehicle, a live axle assembly; a compressor; a unitary motor-generator; a battery; torque transmitting means from said live axle assembly to said compressor and motor-generator and between said compressor and motor-generator; control means, automatically responsive to vehicle running conditions, to cause said motor-generator to act as a motor energized from said battery, to drive said compressor independently of said live axle assembly when said vehicle is standing and, when said vehicle is in motion, to cause said live axle assembly to drive, through said torque transmitting means, said compressor and said motor-generator, said motor-generator arranged to act as a generator to charge said battery, said torque transmitting means including gearing belted to said live axle assembly, said gearing being connected to said motor-generator by a shaft longitudinal to the car, said compressor being placed laterally of said motor-generator and belted to said motor-generator, and means modifying the compressing action of said compressor.

18. In a vehicle, a live axle assembly; a compressor; a unitary motor-generator; a battery; torque transmitting means from said live axle assembly to said compressor and motor-generator and between said compressor and motor-generator; control means, automatically responsive to vehicle running conditions, to cause said motor-generator to act as a motor energized

from said battery, to drive said compressor independently of said live axle assembly when said vehicle is standing and, when said vehicle is in motion, to cause said live axle assembly to drive, through said torque transmitting means, said compressor and said motor-generator, said motor-generator arranged to act as a generator to charge said battery, said torque transmitting means including gearing belted to said live axle

assembly, said gearing being connected to said motor-generator by a shaft longitudinal to the car, and a pneumatically operated clutch between said motor-generator and said live axle assembly.
